AIR BRAKE

William E. Vergan, San Antonio, Tex., assignor to
The New York Air Brake Company, a corpora-
tion of New Jersey

Application June 22, 1931, Serial No. 546,071

3 Claims. (Cl. 303—90)

This invention relates to air brakes, and particularly to the so-called "pipeless" mounting of engineer's brake valves.

In recent years there have been developed commercially what are known as pedestal mounts to support the engineer's brake valve with its related apparatus and also the independent brake valve. The practice has been to mount the pedestal directly on the floor of the cab. In many locomotives, floor mounting is impossible or undesirable, because of lack of floor-space, and in any case the difficulty of making and maintaining pipe connections with the lower side of a base resting on the floor, is a serious factor.

The principal object of the present invention is to provide a mount of the pedestal type, particularly suited to be supported on the end of a locomotive boiler, or other approximately vertical surface. This permits the base to which all pipe connections are made, to be a substantial distance above the floor. Another feature of the invention is the use of a bracket which has independent supporting connections with the base and with the pedestal supported thereby. This ensures rigidity and yet permits ready dismounting of the pedestal without breaking any pipe connections.

The preferred embodiment of the invention is illustrated in the accompanying drawings, in which:

Fig. 1 is a side elevation of the complete device.
Fig. 2 is a fragmentary section showing the bolting lug on the base member.

Fig. 3 is a plan view of the base showing the actual porting of the top face. In this view parts are broken away to show the internal construction.

Fig. 4 is a view looking upward at the lower side of the base.

Fig. 5 is a diagrammatic section, drawn as if all the ports and pipe connections were in a single plane, and intended to make clear the internal interconnection of certain ports, and the location of certain accessory apparatus which may be mounted on said base, and which also is shown diagrammatically.

Referring first to Figs. 1 to 4 inclusive, 11 represents a portion of the boiler shell, for example, the head, and 12 is a wrought steel bracket, whose form is quite clearly shown in Fig. 1. This is connected to the boiler shell 11 by machine screws 13. The bracket 12 is formed with two offsets, the lower one of which produces a shoulder 14 which underlies a portion of the base 15 and engages a heavy lug 16 cast on the lower face of the base 15.

The base 15 is the member to which all the pipes are connected. The lug 16 is connected to the lower offset 14 by a heavy bolt and nuts 17. It will be observed, therefore, that the base portion 15 is supported by the bracket 12 in two ways. In the first place, a portion of the base rests directly

on the top of the offset 14, and in the second place, it is connected to the offset 14 by the bolt 17.

Resting directly on the base 15 is the pedestal portion 18 of the brake valve. This pedestal portion is connected to the second and upper offset 19 formed in the bracket 12 by means of a heavy machine screw 21. The pedestal portion 18 is connected to the base 15 by a plurality of studs, one of which appears at 22 in Fig. 1. The tapped holes formed in the base 15 to receive the studs 10 are clearly shown at 23 in Figs. 3 and 4.

Certain accessory apparatus is mounted on the side of the pedestal portion 18, and some of this is indicated in Fig. 1, for example, the double heading cock 3, relay brake pipe vent valve 9, and mounting 10 for a feed valve (not shown).

Mounted on the upper end of the pedestal portion 18 is an equalizing discharge engineer's brake valve of conventional form, familiar parts thereof being indicated as follows,—equalizing valve portion 24, rotary valve seat portion 25, cap portion 26, and operating handle 27. Bolted to the side of the pedestal portion 18, at 28, is an upstanding bracket 29 which carries the independent brake valve whose cap portion is indicated at 31 and whose operating handle is indicated at 32.

The plane of junction between the pedestal 18 and the base 15 is indicated on Fig. 1 by the line A—A.

It will be observed that the bracket 12 and the attached base 15 produce an overhanging support for the pedestal 18, permitting the ready connection of the pipes leading to and from the engineer's valves. These pipes and their connection to the base 15 are clearly illustrated in Figs. 1 and 4.

The main reservoir pipe 35 is threaded into the base 15 at 36. The brake pipe 37 is threaded into the base 15 at 38. The signal pipe 39 is threaded into the base 15 at 40. The application cylinder pipe 41 is threaded into the base 15 at 42. The distributing valve release pipe 43 is threaded into the base 15 at 44, and the equalizing reservoir pipe 45 is threaded into the base 15 at 46.

An examination of the diagrammatic Fig. 5, and a consideration of the plan view, Fig. 3, will make clear that the main connections 36, 38, 42, 44 and 46 communicate with passages which lead through the base 15 and terminate on the upper face thereof. The connection 36 leads to passage 47; connection 38 to passage 48; connection 42 to passage 49; connection 44 to passage 51, and connection 46 to passage 52. A comparison of Figs. 3 and 4 makes it apparent that the passages just named do not lead straight through the base 15, but are so directed that on the upper face of the bracket they are spaced to register with cor-

responding passages (not shown but present in the pedestal 18).

The signal connection 40 is differently arranged. The passage 53 which registers with a corresponding passage in the pedestal 18, leads to a mounting face on the side of the base 15, against which is bolted the body 54 of a signal fixture. A tight joint between the body 54 and the base 15 is secured by a ported gasket 55. In the body 54 is a filter or strainer 56, to which the passage 53 leads. From the filter a passage 57 leads through a rotary cut-out cock 58 (shown open in Fig. 5, this being its normal condition), through a check valve 59 to a port 61 formed partly in the body 54 and partly in the base 15. The passage 61 leads past the choke 62 and thence to the signal pipe connection 40.

Passage 53 brings air from the usual reducing valve used to feed the signal system from the main reservoir, and passes it through the strainer, cut-out cock and check valve, to the signal line, which is thus charged. Functionally this corresponds to standard practice, but the location of the signal fixture on the base 15 is a convenient feature.

The showing in Fig. 5 is diagrammatic. The showing in Figs. 1 and 3 corresponds to actual construction. In these figures the plug nut 63 is merely a closure to permit access to the check valve 59. The strainer is mounted substantially as shown in Fig. 5.

There is also mounted on the base 15 a dead engine fixture, which is structurally identical with the signal fixture just described. There is a body 64. A passage 65 leads from the brake pipe passage 48 through a strainer 66 and passage 67, past a cut-out cock 68, which is shown in its normal closed position. Beyond the cut-out cock 68 the passage 67 leads past a check valve 69. From the check valve 69 a passage 71 leads through a choke 72 to the main reservoir passage 47.

When the engine is being hauled dead in a train, the cock 68 is set in the open position. In such position air will be drawn from the brake pipe through the strainer and cut-out cock through the check valve and through the choke to charge the main reservoir. The charging rate is controlled by the choke 72. The purpose of charging the reservoir is to have air available to operate the engine and tender brakes, as will be readily understood. The capacity of the choke 62 is so restricted that charging flow from the brake pipe to the main reservoir will not be rapid enough to interfere with control of brake pipe pressure by the engineer's brake valve.

The function of the dead engine fixture is familiar in the art, but its location on the base 15 is a convenient feature. The fact that the signal fixture and the dead engine fixture are identical in construction, is conducive to economy in manufacture.

In Fig. 3 the dead engine fixture is indicated by the numeral 64 applied to the body. The plug cap 73 gives access to the check valve 69. The strainer is mounted in the body 64 substantially as shown in Fig. 5.

If it is desired to house the piping below the base 15 a sheet metal skirt may be applied, and the tapped holes 74 are provided to permit the attachment of this guard. Its use is not, however, essential.

The construction described has many important advantages. The base 15 is above the floor so that the pipes may be readily connected and readily inspected. By releasing the machine screw 21 and studs 22, the pedestal 18 and all connected parts, may be lifted off without requiring the breaking of any pipe connections whatsoever. The provision of a supporting connection, such as the machine screw 21, gives additional support to the pedestal 18, and the fact that the base and the pedestal are both supported by a single bracket, relieves the piping of stresses which would otherwise be encountered.

The particular embodiment of the invention is subject to modification to meet particular requirements. This is especially true of the bracket 11, which should be designed, and may readily be formed, to meet the requirements of particular installations.

While I have described in some detail the particular pipes which are connected to the base, these are merely the pipes that are required by one particular brake valve installation, and it is within the scope of the invention to apply it to specifically different brake valves, which will entail obvious changes in the piping. The dead engine fixture and the signal fixture may be otherwise located without departing from the spirit of the invention.

What is claimed is:—

1. The combination of a support including a bracket for mounting on a boiler or the like and an overhanging ported base connected thereto and formed with means for connecting pipes with said ports; an engineer's brake valve structure; a pedestal ported to register with said base and having a mount for said brake valve; means for connecting said pedestal with said base; and means for connecting said pedestal with said bracket independently of the connection with said base.

2. The combination of an engineer's brake valve; at least one accessory device; a ported pedestal having a mount for receiving said brake valve and connecting it with ports in said pedestal, and a mount for receiving said accessory device and connecting it with a port in said pedestal; a bracket structure adapted for mounting on an approximately vertical surface; a base releasably mounted on said bracket and projecting outward therefrom, said base having in its upper face ports which register with ports in said pedestal, and on its lower face means for connecting pipes with the ports in the base; releasable means for connecting said pedestal and base; and releasable means for connecting said pedestal and bracket.

3. The combination of an engineer's brake valve unit, including a ported pedestal; a base provided with ports adapted to register with the ports in the pedestal, and having means for connecting pipes with said ports in the base; means for releasably connecting said base and pedestal; a bracket having a portion which underlies a portion of said base; and independent releasable connections between the bracket on the one hand, and the side of said base and side of said pedestal on the other hand.
